(57) **ABSTRACT**

A massaging sink pillow structure disclosed herein designed to be placed over the edge of a standard sink used by a barber or beautician for shampooing or rinsing hair. The sink pillow is a waterproof, saddle-shaped structure with a front section designed to be placed against the front outside surface of the sink and a rear section designed to be placed against the front, inside surface of the sink. The sink pillow includes an upper, U-shaped indented section designed to fit into the U-shaped opening on the sink. Mounted inside the sink pillow is a plurality of page motors aligned in rows that are selectively activated to massage the user's neck in one direction or in alternative directions from front-to-back and back-to-front directions when the user's neck is placed over the U-shaped indented section.

MASSAGING SINK NECK REST

This is a continuation in part patent application based on the utility patent application (Ser. No. 11/051,511) filed on Feb. 4, 2005, now U.S. Pat. No. 7,228,573 which was based on the provisional patent application (Ser. No. 60/542,157) filed on Feb. 5, 2004.

BACKGROUND OF THE INVENTION

1. Field of the Invention

The present invention relates to neck rests, and more particularly to neck rests used with sinks that support the neck in a reclined position as the head is placed in the sink for hair treatment, shampooing, or rinsing.

2. Description of the Related Art

When a person's head is tilted rearward into a sink for shampooing or rinsing, the neck is arched rearward and supported by the sides of the sink. Because the hair is soaked with shampoo and water and scrubbed, considerable stress is placed on the back of the neck. If the neck is held in the position too long, the person's neck muscles may become fatigued and blood flow through the neck may be impeded. In some instances, this can cause light-headedness or dizziness.

Vibrating neck rests that support a user's neck over the edge of a sink when shampooing the user's hair is known in the prior art. For example, U.S. Pat. No. 5,393,297 discloses a neck pillow with an internal vibrating mechanism designed to massage the neck muscles when the user's neck is placed on the sink. The vibrating mechanism is made up of a plurality of balls aligned in rows that extend transversely over the pillow's neck supporting surface. The balls in each row are mounted on a transversely aligned rod. The center ball in each row is also mounted on a longitudinally aligned rotating center rod that includes an eccentric. When the center rod is rotated, the eccentric also rotates which causes the center ball to move upward, downward and laterally. The adjacent balls located on the same row wiggle back and forth thereby vibrating the user's neck.

It is this inventor's belief that the vibrational mechanism used in the prior art does not adequately massage the back of the user's neck for several reasons. First, the vibrating action of the mechanisms, do not deeply penetrate the neck. Second, such mechanisms do not promote blood flow in the neck when the head is held in a reclined position over a sink.

SUMMARY OF THE INVENTION

It is an object of the present invention to provide a sink pillow for supporting the neck when the head is held in a reclined position over a sink when shampooing, rinsing or applying a hair treatment to a user's hair.

It is another object of the present invention to provide a sink pillow that deeply massages the muscles in the neck.

It is a further object of the present invention to provide a sink pillow that promotes blood flow in the neck while the neck is supported on the edge of the sink.

These and other objects of the invention are met by the massaging sink pillow disclosed herein designed to be placed over the edge of a standard sink used by a barber or beautician for shampooing or rinsing a customer's hair. Such sinks are typically deep basins with tall sidewalls and a U-shaped opening formed on the front sidewall designed to receive the consumer's neck when the head is reclined rearward into the basin. The sink pillow is a saddle-shaped structure with a front section designed to be placed against the outside surface of the front wall of the sink and a rear section designed to be

2

placed against the inside surface of the front wall of the sink. The sink pillow includes an upper, U-shaped indented section located between the front and rear sections designed to fit into the U-shaped opening formed on the sink.

Mounted inside the sink pillow is a neck massaging mechanism designed to massage the posterior surface of the consumer's neck in one direction or in alternating directions, such as front-to-back and back-to-front directions when the consumer's neck is placed over the U-shaped indented section. In the first embodiment, the neck massaging mechanism includes an elongated pad mounted longitudinally inside the sink pillow. The elongated pad is mounted just below the lower apex of the U-shaped indented section so that it presses and massages the nape of the neck when the neck is placed over the U-shaped indented section. Located below the elongated pad is an eccentric element that rotates and causes the elongated pad to gently lift and roll in a clockwise or counter-clockwise direction. The lift and rolling action applies an upward or downward force to the nape of the neck, which promotes blood flow in the neck.

Located inside the first embodiment of the sink pillow is a printed circuit board (hereinafter referred to as a PCB), which is connected to a D.C. motor that rotates the eccentric element against the elongated member. The PCB is connected to two or more standard or re-chargeable AAA or AA batteries also mounted inside the sink pillow and to the control switch mounted on the sides of the sink pillow. The control switch may be a variable speed control/intensity switch that allows the barber or beautician to control the rate and intensity of the movement of the eccentric member. The device may also include an optional, built-in remote control receiver that communicates with a handheld remote control transmitter that may be operated by the user, barber or beautician. An optional re-charging D.C. female in-plug and battery discharge/charging indicator light may be mounted on the surface of the sink pillow to inform the barber or beautician of the amount of electrical charge in the batteries. In the preferred embodiment the main on/off control switch, variable speed switch, battery discharge meter and the D.C. power plug are all mounted on a control panel located on the lower edge of the pillow's front sidewall.

In the second embodiment, the elongated pad is a saddle shaped structure also designed to nest over the front edge of a beauty salon sink. The pad however is made of flexible polyurethane with a plurality of pager motors embedded therein. In the preferred embodiment, twelve flat circular-shaped pager motors are aligned in three parallel rows longitudinally aligned inside the elongated body. When the pad is placed over the sink the three rows are aligned over the top edge of the sink. There are four pager motors longitudinally aligned and equally spaced apart in each row. The pager motors in the rows are activated sequentially from the row adjacent to the inside edge of the sink to the row adjacent to the front edge of the sink. The three rows are electrically connected to a printed circuit board with a timer mounted thereon that controls the sequential activation of the row of pager motors. A manual switch is connected to the PCB and to the external D.C. electric power adaptor. Loop and hook connector pads between the inside surface of the front section of the pad and the outside front surface of the sink so that the pad is held securely in place over the sink.

In both embodiments, the sink pillow includes an inside layer made of waterproof material and an outside layer made of sufficiently durable, attractive material, such as leather or vinyl.

DESCRIPTION OF THE DRAWINGS

FIG. 1 is a perspective view of the massaging sink pillow disclosed herein.

FIG. 2 is a side elevation view of the invention.

FIG. 3 is a top plan view of the invention.

FIG. 4 is a front elevational view of the elongated pad and the eccentric member showing the movement of the elongated pad.

FIG. 5 is a front plan view of the remote control transmitter.

FIG. 6 is a sectional side elevational view of the second embodiment of the elongated pad with a plurality of pager motors located therein.

FIG. 7 is a partial top plan view of the second embodiment of the elongated pad shown in FIG. 6.

DESCRIPTION OF THE PREFERRED EMBODIMENT(S)

These and other objects of the invention are met by the massaging sink pillow 10 disclosed herein which is designed to be placed over the edge of a standard sink 90 used by a barber or beautician for shampooing or rinsing hair. Such a sink 90 is a deep basin with tall sidewalls 91 and a U-shaped opening 92 formed on the front sidewall 91 designed to receive the user's neck when the head is reclined rearward and into the sink 90. The sink pillow 10 is a saddle-shaped structure with a front section designed to be placed against the outside surface of the front sidewall 91 and a rear section 17 designed to be placed against the front, inside surface of the front sidewall 91. The sink pillow 10 includes an upper, U-shaped indented section 20 designed to fit into the U-shaped opening 92 on the sink 90.

Mounted inside the sink pillow 10 is a neck massaging mechanism 24 designed to massage the user's neck in one direction or in alternating directions from front-to-back and back-to-front directions when the user's neck is placed over the U-shaped indented section 20. The neck massaging mechanism 24 includes an elongated pad 30 longitudinally aligned and mounted inside the sink pillow 10. The elongated pad 30 is mounted just below the lower apex 21 of the U-shaped indented section 20 so that it massages the nape of the neck when the neck is placed on the U-shaped indented section 20. Located below the elongated pad 30 is a rotating eccentric element 35 that rotates around a central axis 41 and causes the elongated pad 30 to lift and roll clockwise or counter-clockwise directions. The lift and rolling action applies an upward or, downward force on the nape of the neck that promotes blood flow there though. Located inside the sink pillow 10 is a printed circuit board 45 (hereinafter referred to as a PCB) that is connected to a D.C. motor 40 that rotates the eccentric element 35 against the elongated member 30. The PCB 45 is connected to two or more standard or re-chargeable AAA or AA batteries 50 also mounted inside the sink pillow 10 and to an on/off control switch 55 mounted on the side of the sink pillow 10. The control switch 55 may include variable speed control/intensity switches 60 that allows the user to control the rate of movement of the eccentric member 30. The sink pillow 10 may also include an optional, built-in remote control receiver 70 that communicates with a handheld remote control transmitter 80 that may be operated by the user, barber or beautician. An optional

re-charging D.C. female in-plug 57 and battery discharge/charging indicator light 56 may be provided to assist the user in recharging the batteries 50. In the preferred embodiment, the main on/off control switch 55, the battery discharge/charging indicating light 56 and the D.C. power plug 57 are all mounted on a panel 52 located on the lower edge of the front sidewall 91.

In the second embodiment shown in FIGS. 6 and 7, the elongated pad 101 is a saddle shaped structure design to nest over the front edge of a beauty salon sink 90. The pad 101 which is made of flexible polyurethane, includes a front section 102, a rear section 103, and plurality of pager motors 120-142 embedded centrally inside the U-shaped indented section of the pad 101. In the preferred embodiment, twelve flat circular-shaped pager motors 120-142 are aligned in three parallel rows 110, 112, 114 longitudinally aligned inside the pad 101. When the pad 101 is placed over the front edge of the sink 90, the three rows are aligned over the sink's top edge. There are four pager motors 120-126, 128-134, and 136-142, longitudinally aligned and equally spaced apart in each row, 110, 112, and 114, respectively. The rows 110, 112, 114 are designed to be activated in sequentially from the row adjacent to the inside edge of the sink to the row adjacent to the front edge of the sink 90. The three rows 110, 112, 114 are electrically connected to a PCB 150 located inside the pad 101. The PCB 150 includes a timer circuit 152 that controls the sequential activation of the three rows 110, 112, 114. A manual switch 160 is connected to an external D.C. electric power adaptor 170. Loop and hook connector pads 180, 185 are disposed between the inside surface of the front leg of the pad 101 and the outside front surface of the sink 90 so that the pad 101 is held securely in place on the sink 90.

In both embodiments, the sink pillow may include an inside layer made of waterproof material and an outside layer made of sufficiently durable, attractive material, such as leather or vinyl.

In the first embodiment, the sink pillow 10 includes an inside layer 11 made of waterproof material and an outside layer 12 made of sufficiently durable, attractive material, such as leather or vinyl. An optional foam layer 13 may be provided to provide greater comfort.

The remote control transmitter 80 includes a body 82 with an increase and decrease intensity control switch 87, 88 respectively, and a visual indicator 89. Mounted inside the transmitter 80 is a PCB 85 with an antenna 84 attached thereto.

In compliance with the statute, the invention described herein has been described in language more or less specific as to structural features. It should be understood, however, that the invention is not limited to the specific features shown, since the means and construction shown, is comprised only of the preferred embodiments for putting the invention into effect. The invention is therefore claimed in any of its forms or modifications within the legitimate and valid scope of the amended claims, appropriately interpreted in accordance with the doctrine of equivalents.

I claim:

1. A massaging sink pillow structure, comprising;
a. a water-proof, saddle-shaped structure with a front section designed to be placed against the front outside surface of the sink and a rear section designed to be placed against the front, inside surface of the sink, said sink pillow includes an upper, U-shaped indented section designed to fit into the U-shaped opening on the sink

- b. a plurality of pager motors aligned in parallel rows which when activated message an individual's neck when placed over said U-shaped indented section of said saddle-shaped structure;
- c. a printed circuit board connected to said pager motors;
- d. a timer connected to said printed circuit board and used to sequentially activate said rows of said pager motors to massaging in one direction from front to back or back to front directions;
- e. a D.C. electrical power source connected to said pager motors and,
- f. a main control switch used to control the flow of electricity from said D.C. electrical power source to said page motors.

10

- 2. The massaging sink pillow, as recited in claim 1, wherein said D.C. electrical power source is a 115 A.C. electrical power adaptor that produces a D.C. electrical current.
- 3. The massaging sink pillow, as recited in claim 2, wherein said saddle is made of polyurethane.
- 4. The massaging sink pillow, as recited in claim 1, further including means for holding said pillow on a sink.
- 5. The Massaging sink pillow, as recited in claim 4, wherein said means for holding said pillow on a sink is at least one pair of hook and loop connectors located on adjacent surfaces of said pillow and said sink.
